(57) **CLAIM**

The ornamental design for a robot, as shown and described.

DESCRIPTION

FIG. 1 is a perspective view of a robot according to our new design, showing a first condition of use in which the top and middle sections of the robot are elevated;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of the robot, now showing a second condition of use in which a top and a middle section of the robot are lowered as compared to FIG. 1;

FIG. 9 is a front view thereof;

FIG. 10 is a rear view thereof;

FIG. 11 is a right side view thereof;

FIG. 12 is a left side view thereof;

FIG. 13 is a top plan view thereof;

FIG. 14 is a bottom plan view thereof;

FIG. 15 is a perspective view of the robot, now showing a third condition of use in which the top and the middle section of the robot are elevated as compared to FIG. 8;

FIG. 16 is a front view thereof;

FIG. 17 is a rear view thereof;

FIG. 18 is a right side view thereof;

FIG. 19 is a left side view thereof;

FIG. 20 is a top plan view thereof; and,

FIG. 21 is a bottom plan view thereof.

The process or period in which the robot transitions from one condition of use to another condition of use forms no part of the claimed design.

The broken-lines illustrate portions of the robot and form no part of the claimed design.
